COMBINED DENTAL CHAIR TOOL SUPPORT AND CONDUIT SHROUD

John N. Jordan, 7501 Mission Road, Prairie Village, Kans.

Filed Dec. 28, 1965, Ser. No. 355

Term of patent 14 years

(Cl. D24—1)

FIGURE 1 is a left side elevational view of my combined dental chair tool support and conduit shroud, shown mounted on a dental chair with the chair and tools being illustrated in dotted lines;

FIG. 2 is a plan view thereof;

FIG. 3 is a back elevational view of one side thereof;

FIG. 4 is a front elevational view of the opposite side thereof; and

FIG. 5 is a right side elevational view of my combined dental chair tool support and conduit shroud, as shown in FIG. 1.

The broken lines are shown for illustrative purposes only.

I claim:

The ornamental design for a combined dental chair tool support and conduit shroud, as shown and described.
